UNITED STATES PATENT OFFICE.

MILTON TODD, OF KIESLING, WASHINGTON.

OVEN-SHELF.

1,279,612.

Specification of Letters Patent. Patented Sept. 24, 1918.

Application filed October 16, 1917. Serial No. 196,925.

To all whom it may concern:

Be it known that I, MILTON TODD, a citizen of the United States, residing at Kiesling, in the county of Spokane, State of Washington, have invented certain new and useful Improvements in Oven-Shelves; and I do hereby declare the following to be a full, clear, and exact description of the invention, such as will enable others skilled in the art to which it appertains to make and use the same.

This invention relates to improvements in supporting devices for the ovens of cooking stoves.

The object of the invention is to provide a support or shelf for cooking stove ovens which may be partially withdrawn, while still supporting the foods which are being cooked so that its major portion remains suspended outside of the oven while the foods are being examined. This construction obviates the necessity of a housekeeper extending the arm into the oven to remove pans and other dishes from the oven shelf for purposes of inspection. Also, the improved construction permits the utensils to be placed upon the shelf, or to be removed therefrom after the baking has been finished, while the shelf is extended from the oven.

With the above objects in view, and such others relating to the details of construction, as may hereinafter appear, my invention will now be fully set forth and described, reference being had to the accompanying drawings.

In the drawings:—

Figure 1 is a sectional view taken horizontally through an oven and showing the shelf in plan.

Fig. 2 is a section on line 2—2 of Fig. 1, and

Fig. 3 is a section on line 3—3 of Fig. 1.

Referring more particularly to the drawings, 1 represents the walls of the oven structure, upon whose sides are secured the angle bars 2 which form the ledges on which the shelf or grid 3 is slidably supported. Said shelf or grid 3 is constructed in any generally accepted manner from sheet metal or cast metal, and, in some cases, may be provided with the longitudinal upturned flanges 4, where the structure requires such a strengthening reinforcement.

In the construction of the grid 3, the side members 5 are formed of practically the same width as the ledges 2, and near their

rear ends have spaced therefrom the outer ends of cleats 6, which at their inner ends are secured to the under sides of one of the transverse members of the grid and extend transversely across the under faces of the side members 5 in such relation that the ledges 2 will be received between the side members and the cleats. Since the cleats 6 are located practically at the rear end of the grid structure, they serve to hold the grid or shelf against tilting movement upon the forward ends of the ledges 2 when the device is extended.

In order to provide a stop against the accidental complete withdrawal of the shelf, I provide the stop pins 7 which are dropped through openings 8 in the ledges 2 near the forward ends thereof, so that the cleats 6 will strike thereagainst when the shelf has been drawn outwardly to the limit provided by the stop pins. The pins 7 are provided with heads 9 whose under sides are beveled to fit corresponding wall portions of the openings 8, and the top surfaces of the heads 80 are rounded, so that in the event that they accidentally project above the upper surfaces of the ledges 2, they will not prevent the even movement of the members 5 over the ledges. Formed in the side members 5 over the heads of the pins 7, when the shelf is entirely within the oven, are the elongated slots 10 which are of such width as to permit passage therethrough of the heads 9 of the pins 7, when said pins are lifted to withdraw them from the openings 8. By this arrangement, the pins may be removed from the ledges when it is desired to completely withdraw the shelf from the oven, it being observed that in the partially withdrawn positions of the shelf the pins are positively held against accidental displacement.

The grid is provided with a handle 11 at its forward end, and in other particulars may possess the characteristics which adapt it to the type of oven in which it is intended to be used. Thus, it will be apparent that the improvements of this invention are adaptable to practically any oven shelf now in use, and that they increase the efficiency of the oven by permitting the more convenient handling of the baking. Not only is the danger of burns materially decreased, but also the liability of spoiling the baking because of the inability to secure a firm hold upon the baking utensils. Therefore, because of the ability to conveniently handle

the dishes by placing them on or removing from the shelf while it is outside of the oven, and also because of the security afforded by the stop devices, the work may be done with 5 greater rapidity and perfection than would be possible without the improved construction.

What I claim as my invention is:—

The combination with an oven of shelf 10 supporting ledges therein provided with openings adjacent the mouth of the oven, headed pins loosely engaged in said openings, a shelf having its side edge portions seated on the ledges and slidable over the

heads of the pins and provided adjacent 15 their forward ends with openings adapted to uncover the heads of the pins to permit their withdrawal when the shelf is slid into the oven and cleat members carried by the rear portion of the shelf and engaging the 20 under surfaces of the ledges and adapted to abut the lower ends of the pins upon forward sliding movement of the shelf.

In testimony whereof, I affix my signature in the presence of a witness.

MILTON TODD.
